UNITED STATES PATENT OFFICE

2,436,092

CURLING ROD

Harry Bonat, New York, N. Y., assignor to Samuel Bonat & Bro., New York, N. Y., a copartnership

Application February 22, 1945, Serial No. 579,244

19 Claims. (CL 132—33)

1

The invention relates to improvements in curling rods, and more particularly to a novelly constructed curling rod of a kind especially useful in the process commonly referred to as cold permanent waving.

In permanent waving of human hair and particularly in the practice of that type of permanent waving known as cold permanent waving, the hair on the head is divided into any required number of individual tresses and said tresses are then individually wound upon curling rods. The wound tresses of hair then are thoroughly saturated with a permanent waving solution which acts to soften the hair or otherwise condition it so that it will conform to its curled condition. After the waving solution has been allowed to act upon the hair tress for a predetermined period of time depending upon the kind of hair being treated, the waving solution is washed out of the wound hair tress with water or other like neutral solution. When the waving solution is removed from the wound tress, the hair then regains its initial structural condition, and when dry and removed from the curling rod it will remain in the wound position to thereby produce the desired curl.

In practice it has been found that satisfactory results can be obtained by the use of this method of cold permanent waving only when the waving solution and the neutralizing solution have been permitted to penetrate to the innermost strands of hair of the wound tress to thereby effect complete saturation thereof. In instances where such complete saturation of all of the hair in the wound tresses is not obtained, the finished curl frequently has portions thereof which do not retain the wound condition and consequently the resulting curl is imperfect, and the hair tress as a whole is non-uniform.

It is, therefore, an object of the present invention to provide a curling rod of the kind referred to, which is constructed in a manner to facilitate complete penetration of the waving and neutralizing solutions throughout the entire body of a curl wound on said rod.

Another object of the invention is to provide a curling rod with novel means therein which is readily removable after the hair tress has been wound thereon tightly so as to cause said wound hair tress to be relatively loose during the application of the solutions.

Another object of the invention is to provide a curling rod of the character referred to which embodies novel structural features enabling the waving and neutralizing solutions to flow freely

2

therethrough and throughout the body of a hair tress wound thereon.

Another object of the invention is to provide a curling rod of the kind disclosed with novelly constructed easily detachable means to clamp the hair tress to the curling rod at the start of the hair winding operation.

Another object of the invention is to provide a durable curling rod which is easy and inexpensive to manufacture, simple to use, and highly efficient.

Other and further objects of the present invention will be apparent from the following description and claims and are illustrated in the accompanying drawings which, by way of illustration, show preferred embodiments and the principle thereof and which are considered to be the best mode contemplated for applying that principle. Other embodiments of the invention embodying the same or equivalent principle may be used and structural changes may be made as desired by those skilled in the art without departing from the present invention and the purview of the appended claims.

25 In the drawings:

Fig. 1 is a perspective view of a curling rod embodying features of the present invention.

Fig. 2 is an enlarged side elevational view of the curling rod showing parts broken away and a hair tress wound thereon.

Fig. 3 is a top plane view of the curling rod shown in Fig. 2, and broken away in part substantially along the line 3—3 of said figure.

Fig. 4 is a longitudinal central sectional view of the curling rod body, showing a hair tress wound thereon.

Fig. 5 is an enlarged side elevational view similar to Fig. 2 of a curling rod embodying modified features of construction.

40 Fig. 6 is a longitudinal sectional view of the curling rod shown in Fig. 5.

Fig. 7 is an enlarged transverse sectional view taken on line 7—7 of Fig. 5.

Fig. 8 is an enlarged transverse sectional detail view taken on line 8—8 of Fig. 6.

Fig. 9 is a perspective view of a curling rod embodying additional modified features of construction.

The curling rod embodying features of the present invention and illustrated in Figs. 1 to 4, inclusive of the accompanying drawings consists of a body portion generally indicated at 11 and a holder generally indicated at 12. The body portion 11 is fashioned in the form of a substantially cage-like structure including circular end

walls 13 and 14 connected together by a plurality of bars 15. The bars 15 preferably are formed of lengths of relatively stiff shape-retaining wire or thin rods having their ends firmly secured, as best shown in Fig. 4, into the end walls 13 and 14 respectively, as by riveting their ends as at 16. In the form of the curling rod body illustrated in these figures, there are three bars 15, each of which is suitably curved or arched lengthwise so that the intermediate portion of the body 11 formed in part thereby is of a diameter considerably smaller than the diameter of the circular end walls 13 and 14. This mode of construction is desired primarily because when the tress of hair is wound upon the body, said tress tapers downwardly and outwardly towards its ends as the winding increases, consequently the reduced medial diameter of the curling rod prevents excessive building up of the hair tress at the longitudinal center of the curling rod.

The curling rod body 11 is adapted to include a fourth bar 17 which likewise is formed of thin shape-retaining wire or of a thin rod, and this bar is mounted in the body end walls 13 and 14 for easy separation therefrom or attachment thereto. The bar 17 is of greater length than the over-all length of the curling rod body so that one end thereof, as at 18, may be firmly embedded in and secured to a handle portion 19 of the holder 12. Thus it will be seen that the bar 17 and handle portion 19 constitute the holder 12 and that said holder may be associated with the body 11 in a manner to be described presently so that the bar 17 thereof constitutes a complementary portion of said body.

To this end, the end wall 14 of the body 11 is provided with a hole or recess 21 on its inside face to receive the end of the bar 17 when the latter is mounted in association therewith as best shown in Fig. 3, and the other end wall 13 preferably is provided with a radial recess 22, best shown in Figs. 3 and 4, of sufficient depth to enable the bar 17 to lie therein when the free end of said bar is engaged in the hole or recess 21. When the bar 17 is properly positioned in the hole 21 and recess 22, it is held against inadvertent displacement by an interlocking arrangement provided on the body 11 and handle portion 19. As shown, the end wall 13 is formed on its outside face with an axial stem 23 adapted to be received within an axial recess 24 provided in the end of the handle portion 19 carrying the bar 17.

To assemble the holder 12 and body 11, the recess 24 is fitted over the stem 23 and the holder then is moved towards the body portion until the free end of the bar 17 engages in the hole 21 in the end wall 14. When thus assembled the curling rod body includes the three arcuate bars 15 and the straight bar 17 which together define, in section, a substantially diminishing tubular body as the medial portion thereof is approached.

In use, the free end of a hair tress is held or clamped against the medial portion of the body 11, preferably by means of a clamp 20 pivotally mounted on one of the bars 15, and the curling rod then is rotated to wind the tress thereon. When the hair tress is completely wound upon the body 11, the curling rod is located close to the scalp and the hair tress is then secured against unwinding by any suitable means such as by means of a strand 25 of resiliently flexible material such as rubber, or the like. The securing strand 25 has one end secured detachably to one end of the body 11 as by having an apertured

end 26 fitted over a boss 27 provided on the outside face of the end wall 14. The boss 27 preferably is suitably recessed circumferentially, as at 28, to receive the strand and prevent inadvertent displacement thereof. It might be noted at this time that the boss 27 is useful to facilitate grasping of the end of the curling rod, upon which it is provided, during the winding operation.

Prior to securing the wound tress of hair to the curling rod by means of the strand 25, the holder 12 is removed from the body 11 as by withdrawing the same from engagement with the stem 23, which removal also withdraws the bar 17 from the body 11 and from within the wound hair tress. The free end of the strand 25 is apertured as at 29, and this apertured end is engaged over the now exposed stem 23, as best shown in Fig. 4, to thereby prevent the wound tress from unwinding.

It should be observed upon viewing Fig. 4 that removal of the bar 17 from the body 11 enables the wound hair tress to become comparatively loose upon the body 11, while at the same time it retains its wound condition. This looseness of the wound hair tress is necessary to satisfactory practice of cold permanent waving because of the need for effecting complete saturation of all of the strands of hair in the wound hair tress. Such saturation obviously is exceedingly difficult and frequently impossible to attain when the hair tress is wound tightly upon the curling rod body as during the initial winding. The cage-like structure of the body 11 also facilitates thorough penetration and complete saturation of the hair tress because of its open construction which enables the solutions to flow freely throughout the entire bulk of the wound tress and through the interior of the curling rod body, as when an excessive amount of the solutions flows from the uppermost portion of the wound tress through said cage-like body and down onto the lower interior face thereof. After the curl has been treated with the waving solution and with the neutralizing solution, which is effective to wash out the waving solution, it may be dried while remaining on the curling rod body 11, or it may be removed from said curling rod body prior to drying, easily and quickly by disengaging the strand 25 from the stem 23 and unwinding.

The curling rod shown in Figs. 5 to 8 inclusive, is substantially like that described hereinabove and like numerals are used to identify corresponding parts. However, in this embodiment of the invention at least one of the bars 15, such as 55 for example the one identified as 15a, is mounted in the end walls 13 and 14 in such manner that it may be shifted into various positions so as to decrease the tension on the wound hair tress to thereby enable said tress to acquire the desired looseness. As best shown in Figs. 7 and 8 the bar 15a has its ends engaged in cam-like slots 31 formed on the inside faces of said end walls. Each of the slots 31 includes a radial portion 32 and a circumferential portion 33 and is suitably formed at the juncture of said portions 32 and 33 with a detent projection 34. The slots 31 are of such width as to snugly receive the ends of the bar 15a and when said bar is in its outermost position, as best shown in Fig. 7, its ends rest in the circumferential portions 33 of said slots to dispose the bar substantially in the same circumferential plan as the fixed companion bars 15 and removable bar 17. The hair tress is clamped to the curling rod by clamp 20 and then is wound 70 upon the body of the curling rod while the mov-

able bar is in this position. After the hair tress has been fully wound thereon and the holder 12 is removed to withdraw the bar 17 from within the curl, the bar 15a is moved past the detent projection 34, in each slot, so that it may drop into the slot portion 32 so as to further increase the looseness of the hair tress wound on said rod.

The curling rod illustrated in Fig. 9 is substantially like the curling rods previously described herein and like numerals are used to identify corresponding parts. This embodiment of the curling rod includes diametrically opposed connecting bars 15 extending between the end walls 13 and 14 and includes the removable bar 17 constituting a part of the holder 12. The curling rod is provided with a substantially T-shaped clamp consisting of a stem portion 35 and a cross head 36. The cross head 36 is of a length to be fitted between the longitudinal bars 15 as shown, and its ends are suitably formed to be journaled in recesses in said bars so as to provide a pivotal mounting for the clamp. It should be evident that, when the end of the hair tress is laid across the two bars 15, the clamp may be easily moved from an open position into a position against the hair tress so as to firmly bind the hair tress to the curling rod during the initial winding operation.

It should be understood at this time that while the present disclosure shows a preferred number of bars 15 and 15a, the number of such bars as may be included in the body 11 of the curling rod may be increased or decreased to suit particular conditions of use and problems of manufacture and that other variations in the detail construction of each of the curling rods illustrated may be made without departing from the spirit of the invention and the scope of the appended claims.

I claim:

1. A curling rod comprising, in combination, a substantially cylindrical cage-like body including end members and circumferentially spaced longitudinal bars extending therebetween, and a removable handle associated with said body, said handle having one of said bars connected thereto for removal from the body with said handle.

2. A curling rod comprising, in combination a cage-like tubular body having a medial portion of smaller diameter than its end portions, a handle fitted for easy removal onto one end of said body, and means on said handle and removable therewith constituting a portion of said tubular body.

3. A curling rod comprising, in combination, a cage-like body adapted to have a hair tress wound thereon, a wall at each end of said body, circumferentially spaced bars extending between said end walls, at least one of said bars being detachably connected to said end walls for removal after a hair tress has been wound on said cage-like body, and means coextensive with the curling rod and detachably secured to said end walls to retain the hair tress wound thereon.

4. A curling rod comprising, in combination, a cage-like body adapted to have a hair tress wound thereon, a wall at each end of said body, at least three bars extending between and anchored at their ends to said end walls, at least one bar being detachably connected to said end walls for removal after a hair tress has been wound on said cage-like body, and means coextensive with the curling rod and detachably secured to said end walls to retain the hair tress wound thereon.

5. A curling rod comprising, in combination a cage-like body adapted to have a hair tress wound thereon, a wall at each end of said body, circumferentially spaced bars extending between said end walls, said bars being connected to said end walls at the circumferential margin thereof, at least one of said bars being detachably connected to said end walls for removal after a hair tress has been wound on said cage-like body, and means coextensive with the curling rod and detachably secured to said end walls to retain the hair tress wound thereon.

6. A curling rod comprising, in combination a cage-like body adapted to have a hair tress wound thereon, a wall at each end of said body, circumferentially spaced bars extending between said end walls, at least one of said bars being removable after a hair tress has been wound on said cage-like body, said removable bar being engaged in a hole in one of said end walls and having its other end rested in a radial recess in the other end wall, and means coextensive with the curling rod and detachably secured to said end walls to retain the hair tress wound thereon.

7. A curling rod comprising, in combination a cage-like body adapted to have a hair tress wound thereon, a wall at each end of said body, circumferentially spaced bars extending between said end walls, at least one of said bars being removable after a hair tress has been wound on said cage-like body, said removable bar being engaged in a hole in one of said end walls and having its other end rested in a radial recess in the other end wall, and means coextensive with the curling rod and detachably secured to said end walls to retain the hair tress wound thereon.

8. A curling rod comprising, in combination, a cage-like body adapted to have a hair tress wound thereon, a wall at each end of said body, at least three bars extending between and anchored at their ends to said end walls, said bars being connected to said end walls at the circumferential margin thereof, at least one bar being removable after a hair tress has been wound on said cage-like body, said removable bar being engaged in a hole in one of said end walls and having its other end rested in a radial recess in the other end wall, and means coextensive with the curling rod and detachably secured to said end walls to retain the hair tress wound thereon.

9. A curling rod comprising, in combination, a cage-like body adapted to have a hair tress wound thereon, a wall at each end of said body, circumferentially spaced bars extending between said end walls, at least one of said bars being detachably connected to said end walls for removal after a hair tress has been wound on said cage-like body, a handle on said removable bar, means coextensive with the curling rod and detachably secured to said end walls to retain the hair tress wound thereon, and means on one of said end walls engageable in said handle to retain the handle and bar thereon in place on the curling rod.

10. A curling rod comprising, in combination, a cage-like body adapted to have a hair tress wound thereon, a wall at each end of said body, circumferentially spaced bars extending between said end walls, at least one of said bars being detachably connected to said end walls for removal after a hair tress has been wound on said cage-like body, a handle on said removable

bar, means coextensive with the curling rod and detachably secured to said end walls to retain the hair tress wound thereon, and a projection on one of said end walls engageable in said handle to retain the handle and bar thereon in place.

11. A curling rod comprising spaced circular end members and bars connecting said end members to provide a cylindrical cage-like body, at least one of said bars being mounted in said end members for movement radially.

12. A curling rod comprising, in combination, a tubular cage-like body adapted to have a hair tress wound thereon tightly, a wall at each end of said body, circumferentially spaced bars extending between and mounted at their ends at said end walls, and at least one of said bars being mounted in said end walls for movement inwardly radially after a hair tress has been wound on said cage-like body to loosen the wound tress.

13. A curling rod comprising, in combination, a tubular cage-like body adapted to have a hair tress wound thereon tightly, a wall at each end of said body, circumferentially spaced bars extending between and mounted at their ends at said end walls, means to retain the hair tress wound on said rod, and at least one of said bars being mounted in said end walls for movement inwardly radially after a hair tress has been wound on said cage-like body to loosen the wound tress.

14. A curling rod comprising, in combination, a tubular cage-like body adapted to have a hair tress wound thereon tightly, a wall at each end of said body, circumferentially spaced bars extending between and mounted at their ends at said end walls, and at least one of said bars being movable inwardly radially after a hair tress has been wound on said cage-like body to loosen the wound tress, said end walls being slotted to receive the ends of the movable bar.

15. A curling rod comprising, in combination, a tubular cage-like body adapted to have a hair tress wound thereon tightly, a wall at each end of said body, circumferentially spaced bars extending between and mounted at their ends at said end walls, at least one of said bars being movable inwardly radially after a hair tress has been wound on said cage-like body to loosen the wound tress, said end walls being slotted to receive the ends of the movable bar, and means fashioned in said slots to hold the movable bar outwardly radially while the hair tress is being wound on said rod.

16. A curling rod comprising spaced end members, and a plurality of bars connected to both of said end members to provide a cylindrical cage-like body adapted to have a tress of hair wound thereon in substantially tight condition, at least one of said bars being separable from said body after a tress of hair has been wound thereon so as to loosen the wound tress of hair on said body, and means for securing said tress against unwinding.

17. A curling rod including a plurality of bars forming a cylindrical cage-like body adapted to have a tress of hair wound thereon in substantially tight condition, at least one of said bars being separable from said body after a tress of hair has been wound thereon so as to loosen the wound tress of hair on said body, and means for securing said tress against unwinding.

18. A curling rod comprising spaced end members, at least two bars fixedly connected to said end members, an auxiliary bar connecting said end members but being removable therefrom, said bars arranged to provide an elongated body and adapted to have a hair tress wound thereon, a clamping member pivotally mounted on one of said fixed bars and arranged to secure to said body a hair tress during the initial winding thereof.

19. A curling rod comprising spaced end members, a plurality of bars connecting said end members and arranged to provide an elongated body adapted to have a hair tress wound thereon, at least two of said bars being fixedly connected, and at least one of said bars being removably supported, and a clamp member pivotally mounted on one of said fixed bars and arranged to secure to said body a hair tress during the initial winding thereof.

HARRY BONAT.
